Inventor:

Harold J. Horn
by his Atty:

Philip Sawyer, Prox & Kennedy.

UNITED STATES PATENT OFFICE.

HAROLD J. HORN, OF TRENTON, NEW JERSEY, ASSIGNOR TO JOHN A. ROEBLING'S SONS COMPANY, A CORPORATION OF NEW JERSEY.

TERMINAL FOR WIRE AND WIRE ROPE.

1,249,093.

Specification of Letters Patent.

Patented Dec. 4, 1917.

Application filed October 20, 1915. Serial No. 57,018.

To all whom it may concern:

Be it known that I, HAROLD J. HORN, a citizen of the United States, residing at Trenton, county of Mercer, and State of New Jersey, have invented certain new and useful Improvements in Terminals for Wire and Wire Rope, fully described and represented in the following specification and the accompanying drawings, forming a part of the same.

The especial object of the present invention is to provide an improved terminal or attaching end for the wire rope stays of aeroplanes, but the terminal of the present invention is applicable, also, to other uses.

I aim especially to provide a terminal which shall develop the full strength of the wire or wire rope and which shall secure a better lock under strain than those heretofore in use, while at the same time simple and cheap in construction.

For a full understanding of the invention, a detailed description of terminals embodying the invention in preferred forms will now be given, in connection with the accompanying drawings forming a part of this specification, and the invention then particularly pointed out in the claims.

In the drawings,

Figure 1 is a side view of a terminal in the form preferably used, where especial strength is required.

Fig. 2 is an edge view of the same.

Fig. 3 is a longitudinal section on the line 3 of Fig. 2.

Fig. 4 is a cross section on the line 4 of Fig. 3.

Figs. 5 and 6 are views corresponding to Figs. 1 and 2, showing a modified construction.

Fig. 7 is a view similar to Figs. 1 and 5, showing a terminal similar to Fig. 5 but without the thimble inside the rope wire.

Fig. 8 is a cross section on the line 8—8 of Fig. 7.

Fig. 9 is a terminal similar to that of Fig. 7, but with a double eye.

Referring to the drawings and now especially to Figs. 1 to 4, *a* is the wire or wire rope on which the terminal is formed, which is bent to form an eye 10 at the end with a thimble 11 therein, this thimble being shown as open at the side for insertion of an eye or ring before the terminal is formed, if desired,

The thimble 11 is formed with a long wedge portion 12 extending along the rope *a* and between the two sides of the loop forming the eye 10, this wedge 12 preferably being grooved on opposite sides for 60 the rope. A tapering ferrule 13 formed of helically wound wire incloses the wedge 12 and the ropes on opposite sides of the wedge, and the end 14 of the rope *a* is bent back around the inner end of the ferrule and over it, and secured in place so as to prevent it being straightened out by pull on the eye. For holding this bent end 14 most strongly in position so that pull upon the eye shall lock the ferrule firmly, the 70 wires of the rope end 14 are preferably spread out as shown, and secured between layers of comparatively small wires 1 wound about the ferrule 13 and about the rope end 14.

It will be seen that this construction provides an exceedingly strong terminal, in which the effect of strain is to lock the parts firmly together by the friction caused by crowding the ropes and wedge together as 80 the ferrule is forced up on the wedge, and that this pressure is secured throughout the length of the wedge and ferrule by the preferred tapering form of the ferrule. The taper of the inner end of the eye also 85 avoids danger of breakage at this point, and aids in securing the proper action of the wedge and ferrule. No solder or other similar connection is used throughout the terminal, and the full strength of the wire 90 or wire rope is secured. The construction, also, is simple, cheap and convenient of manufacture.

In Figs. 5 and 6 a construction similar to that of Figs. 1 to 4 is shown, except that 95 the thimble 15 is closed instead of open at the side, and the rope end 14 is secured simply by bending it back over the tapering ferrule 13 and bending a stiff wire 2 about the ferrule and rope end. This construction will be found satisfactory for conditions not requiring the especial strength of the terminal shown in Figs. 1 to 4.

In Figs. 7 and 8 a construction is shown similar to that of Figs. 5 and 6, except that 105 no thimble is used within the eye 10, and a separate wedge 16 is between the ropes inclosed by the ferrule 13 and acts in the same manner as in the constructions previously described. The construction shown in Fig. 9 110

is the same as that shown in Figs. 7 and 8, except that the rope *a* is bent around to form a double eye 17, thus securing greater strength, as compared with the construction shown in Figs. 7 and 8.

What I claim is:

1. A terminal for wire or wire rope having the wire or wire rope looped to form an eye, a wedge between the sides of the loop tapering from the eye and a ferrule inclosing the sides of the loop and the wedge, the end of the wire or wire rope being bent back around the inner end of the ferrule and having the bent end secured to prevent straightening.
2. A terminal for wire or wire rope having the wire or wire rope looped to form an eye, a wedge between the sides of the loop tapering from the eye, and a tapering ferrule inclosing the sides of the loop and the wedge, the end of the wire or wire rope being bent back around the inner end of the ferrule and having the bent end secured to prevent straightening.
3. A terminal for wire or wire rope having a wire or wire rope looped to form an eye, a wedge between the sides of the loop, and a ferrule formed of helically wound wire inclosing the sides of the loop and the wedge, the end of the wire or wire rope being bent back around the inner end of the ferrule and having the bent end secured to prevent straightening.
4. A terminal for wire or wire rope having the wire or wire rope looped to form an eye and a thimble within the eye, the inner end of which thimble forms a wedge be-

tween the sides of the loop, and a tapering ferrule inclosing the sides of the loop and the wedge, the end of the wire or wire rope 40 being bent back around the inner end of the ferrule and having the bent end secured to prevent straightening.

5. A terminal for wire or wire rope having the wire or wire rope looped to form 45 an eye and a thimble within the eye, the inner end of which thimble forms a wedge between the sides of the loop, a ferrule formed of helically wound wire inclosing the sides of the loop and the wedge, the end 50 of the wire or wire rope being bent back around the inner end of the ferrule and spread out, and a winding of small wires upon the ferrule inside and outside the rope-end for holding the rope end against 55 straightening.

6. A terminal for wire or wire rope having the wire or wire rope looped to form an eye, a wedge between the sides of the loop, a ferrule formed of helically wound wire 60 inclosing the sides of the loop and the wedge, the end of the wire or wire rope being bent back around the inner end of the ferrule and spread out, and a winding of small wires upon the ferrule inside and outside 65 the rope end for holding the rope end against straightening.

In testimony whereof, I have hereunto set my hand in the presence of two subscribing witnesses.

HAROLD J. HORN.

Witnesses:

GORDON W. WALLER,
PETER A. KUCKER.
